(57) **CLAIM**

The ornamental design for a fishing lure, as shown and described.

DESCRIPTION

FIG. 1 is a top plan view of the fishing lure of this invention;
FIG. 2 is a front elevational view thereof;
FIG. 3 is a side elevational view thereof, the side opposite
being a mirror image thereof;
FIG. 4 is a rear elevational view thereof;
FIG. 5 is a bottom plan view thereof; and
FIG. 6 is an isometric view thereof;
FIG. 7 is a top plan view of an alternative embodiment
fishing lure of this invention;
FIG. 8 is a front elevational view thereof;
FIG. 9 is a side elevational view thereof, the side opposite
being a mirror image thereof;
FIG. 10 is a rear elevational view thereof;
FIG. 11 is a bottom plan view thereof; and
FIG. 12 is an isometric view thereof;
FIG. 13 is a top plan view of another alternative embodiment
fishing lure of this invention;
FIG. 14 is a front elevational view thereof;
FIG. 15 is a side elevational view thereof, the side opposite
being a mirror image thereof;
FIG. 16 is a rear elevational view thereof;
FIG. 17 is a bottom plan view thereof; and
FIG. 18 is an isometric view thereof;
FIG. 19 is a top plan view of an alternative embodiment
fishing lure of this invention;
FIG. 20 is a front elevational view thereof;
FIG. 21 is a side elevational view thereof, the side opposite
being a mirror image thereof;
FIG. 22 is a rear elevational view thereof;
FIG. 23 is a bottom plan view thereof; and
FIG. 24 is an isometric view thereof;
FIG. 25 is a top plan view of another alternative embodiment
fishing lure of this invention;
FIG. 26 is a front elevational view thereof;
FIG. 27 is a side elevational view thereof, the side opposite
being a mirror image thereof;
FIG. 28 is a rear elevational view thereof;
FIG. 29 is a bottom plan view thereof; and
FIG. 30 is an isometric view thereof.
